Patented Aug. 9, 1921.

UNITED STATES PATENT OFFICE.

THOMAS LUND, OF BEVERLY, MASSACHUSETTS, ASSIGNOR TO UNITED SHOE MANUFACTURING CORPORATION, OF PATERSON, NEW JERSEY, A CORPORATION OF NEW JERSEY.

HEEL-COMPRESSING MACHINE.

1,386,639.

Specification of Letters Patent. Patented Aug. 9, 1921.

Application filed June 26, 1919. Serial No. 306,868.

To all whom it may concern:

Be it known that I, THOMAS LUND, a citizen of the United States, residing at Beverly, in the county of Essex and State of Massachusetts, have invented certain Improvements in Heel-Compressing Machines, of which the following description, in connection with the accompanying drawings, is a specification, like reference characters on 10 the drawings indicating like parts in the several figures.

This invention relates to machines for operating upon boot and shoe parts, and more particularly to the means for feeding 15 or moving the boot or shoe part to position for treatment by the machine.

The efficiency of such machines and their productive capacity depend to some extent upon the amount of time necessary to feed 20 the shoe part or article to the position it is to occupy when the machine takes charge of it for treatment. It is, therefore, desirable to feed or move the boot or shoe part to treating position by mechanical means, 25 preferably automatic in character, and to economize, as far as possible, the amount of time occupied in placing the part or article in final position relative to the portions of the machine by which it is to be treated. 30 This necessitates a rapid movement of the automatic feeding means and a very close time relation between the operative movement of the feeding means and the movement of the power operated means by which 35 the shoe part or article is to be treated and into operative relation to which the shoe part or article is moved by the feeding means. This condition is especially conspicuous when the machine is run at high 40 speed, as is customary with many machines of types to which the present invention is applicable, and experience has demonstrated that, under such circumstances, the article being fed to position for treatment is liable 45 to become misplaced with respect to the feeding means and thus to fail to be placed in proper operative relation to the means by which it is to be treated. Such misplacement may be caused by variations of inertia 50 or momentum deranging slightly the time relation between the feeding means and the operating means and, since this time relation is necessarily very close, a slight variation therein may involve such serious consequences as failure of the shoe part or

article to be introduced into proper treating position, by reason of it striking a portion of the operating means.

When any contingency occurs which causes failure properly to locate the boot or shoe part for treatment, not only is the productive capacity of the machine impaired, but the boot or shoe part, or, it may be, a portion of the machine itself, is liable to injury. It is desirable, therefore, to have 60 the boot or shoe part advance toward treating position rapidly to economize time consumption and to bring it to rest in proper position relative to the treating means without the occurrence of the objectionable contingencies above noted. 65

An important feature of the present invention, therefore, consists in the provision of improved means for so controlling the action of the feeding means as to insure 70 against the occurrence of the difficulties above described. This feature of the invention is capable of a variety of specific embodiments, but the desired result is preferably accomplished by giving the feeding 75 means a relatively rapid feeding movement until the boot or shoe part is in proximity to its final position, whereupon means are automatically rendered operative to cause 80 a momentary retardation or pause in the feeding movement until a collision between the work and the operating means becomes 85 impossible and the work may be deposited with certainty and accuracy in proper operating position. 90

This characteristic feature of the present invention may be advantageously employed in a variety of machines for treating boot and shoe parts, such, for instance, as heels, top-lifts, counter blanks, and the like, where 95 the part or article is to be treated after having been fed or moved to a position relative to the treating means. In some machines for treating boot and shoe parts, the present invention has special and additional adaptation, and, while generally applicable to any of the machines above indicated, it will hereinafter be described in connection with a compressing machine for compressing or molding parts of boots or shoes, such, 100 for instance, as heels and top-lifts. A machine of this general type is shown and described in the United States Patent to Charles L. Allen No. 776,823, dated December 6, 1904, wherein the blanks to be com- 105

110

pressed are placed between pressure exerting members which are relatively movable toward and from each other.

In the machine of the patent, one of the pressure exerting members consists of a mold comprising side and breast portions and a top lift plate which are carried by a head movable toward or from a fixed heel seat die forming the other pressure exerting member, and, during the separating movement of the pressure exerting members, heel ejecting and feeding means act to discharge a previously compressed or molded heel and to insert a heel to be compressed between the pressure exerting members. This machine has been successful and commercially efficient in producing compressed or molded blanks, such as heels and top lifts, and in connection with such machine the broad features of the present invention may be advantageously employed.

In recent years the height and styles of heels have become more and more extreme, particularly heels for women's shoes, and compressing machines which were heretofore adapted to successfully compress heels of usual height, have become unsuited to treat heels of the more recent height and style, because during the feed movement of such high heels into position between the pressure exerting members, they are liable to strike the side of one of the compressing members and fail to reach compressing position. In a machine such as that of the Allen patent, for instance, where the inward or feed movement of the heel takes place during the separating movement of the pressure exerting members, the advancing rear upwardly extending edge of the heel is liable to contact with the upper die or follower before the separating movement of the pressure exerting members has been sufficient to permit the introduction of such extreme heel between them. This fact may be evident where any heel of unusual height is fed toward heel compressing position, but is particularly manifest where the heel is of such extreme height and style as the "Louis" or "Cuban" heel, in which the heel seat portion toward the rear of the heel extends upwardly to a considerably greater degree than at the breast of the heel.

An important feature of the invention in this connection, therefore, consists of means for retarding the feed movement of the feeding means until the separating movement of the pressure exerting means has been sufficient to receive the heel between them. This retardation in the feed movement may be effected by causing the momentary slow up of the feed movement as the heel approaches compressing position, or it may be by a momentary pause in the feed movement.

Another important feature of the inven-

tion consists in a retarding device which is effective during the feed movement of the heel toward treating position. This action of the retarding device may be variously contrived to suit condition of use, but in the present instance is caused by the relative separating movement of the pressure exerting means.

Other features of the invention and novel combinations of parts in addition to those above noted will be hereinafter described in connection with one good practical form of the invention and then definitely set forth by the claims.

In the drawings:—

Figure 1 is a vertical section from front to rear of a machine embodying the present invention, only sufficient of the entire machine being shown as is necessary to make clear the association of the invention therefor;

Fig. 2 is an enlarged detached detail showing one position of parts constituting one form of retarding means;

Fig. 3 is a view similar to that of Fig. 2 with the parts of the retarding means shown in another position; and

Fig. 4 is a similar view showing the parts of the retarding means in still another position.

The invention is shown, in the present instance, as embodied in a heel compressing machine, such as disclosed by the above mentioned Allen patent, and it will therefore, not be necessary to describe in detail the various features of the machine which are not directly concerned with the present invention, because these are fully set forth in the Allen patent to which reference may be had. The construction disclosed by the Allen patent is selected for the embodiment of the present invention as a matter of convenience in describing and making clear the construction and mode of operation of the invention itself and its combination with compression members of a compressing machine, but it is to be understood, of course, that the invention may be associated and combined with any machine where the conditions require a retardation or pause in the feeding movement of the feeding means.

The main frame of the machine in the drawings is indicated at 1, which may be of suitable character to support the operating parts, or as shown in the Allen patent mentioned. Mounted for reciprocating movement in suitable guideways formed in the sides of the rigid frame is a head 2, with which is combined one of the pressure exerting members. The head 2 is given reciprocating movement by toggles 3, 4 connected by a link 5 to suitable actuating means.

The compression members, in the present instance of the invention, comprise the heel seat die or follower 6 (Fig. 1) which is rig-

idly supported by the overhead arch of the main machine frame, and a reciprocating heel mold which may comprise side members 7, a breast plate 8 and a top lift plate 9, the latter being relatively movable of the die formed by the side and breast members as fully explained in the Allen patent.

The top lift plate 9 is provided with or mounted upon a support 10 which may be actuated at times to move the top lift plate relative to the mold members by means of an arm 11, substantially as fully described in the Allen patent above mentioned. A spring actuated limiting stop 12 engages a longitudinal recess in the support 10 to limit the reciprocating movement of the top lift plate under the actuation of the arm 11.

The reciprocating head 2 has a forward extension 13 (Fig. 1) which constitutes a table or support for a feeding mechanism. The feeding and ejecting mechanism may comprise among its parts the slide 14 movable on suitable guideways provided in the upper portion of the table 13. Suitable heel blank clamping arms may be carried by the slide 14, the rear ends of which clamping arms at 15 (Fig. 1) constitute shoulders or pushers to contact with and push a compressed heel from the top lift plate and out of the machine as indicated in Fig. 1, as the slide is moved to position a heel blank for the action of the pressure members, in which respects the parts may be similar to those fully described in the Allen patent.

The slide 14 has a tail piece 16 pivotally connected to it at 17, and held in normal working position as indicated in Fig. 1 by a latch 18. Projecting from the tail piece 16 is a lug 19 carrying a pin 20 which engages the bifurcated end 21 of the arm 22 of a bell-crank lever pivoted at 23 on the projection or table 13, the construction being such that by manipulating the latch 18 the tail piece may be lifted to disengage the pin 20 from the bifurcated end 21 to permit the feed slide 14 to be removed from the machine when desired. The other arm 24 of the bell-crank is provided with a pin or roll 25 which engages an elongated slot 26 in a link or rod 27 which extends through a sleeve 28 pivoted to the machine frame 1 at 29. A spring 30 within the sleeve 28 normally acts against the shoulder 31 of the rod 27 to force the rod longitudinally outward relative to the sleeve 28.

The parts thus far described may be substantially as in the Allen patent above mentioned, the slot 26 forming a lost motion connection between the rod 27 and the bell-crank 22, 24. As described in the Allen patent, during the first part of the rise of the reciprocating head 2, the roll or pin 25 travels in the slot 26, and the bell-crank lever is not actuated to move the feeding slide 14. During the latter part of the

rise of the head 2, the roll or pin 25 comes to the end of the slot 26, and therefore, the bell-crank lever 22, 24 is actuated to move the slide in a direction to retract the heel blank holder or feeding device in a direction 70 away from the mold. When the head 2 begins to descend after a compressing operation, the roll or pin 25 again travels the length of the slot 26 without actuating the bell-crank 22, 24, or causing the slide 14 to 75 be moved, thus giving ample time for the workman to insert a heel blank in the feeder or clamp; but after the roll or pin 25 reaches the lower end of the slot 26, the bell-crank lever is actuated to move the slide 14 to 80 present the blank to the pressure exerting means and to eject a previously compressed blank.

The forward movement of the feeding means or slide 14 to eject a compressed heel 85 and place a blank in position between the pressure exerting members to be compressed, therefore, takes place as the pressure exerting members move relative in a direction of separation, and in the treatment of heels 90 of ordinary height, the mechanism hereinbefore described and also described in the patent to Allen, effectively serves to feed such heels into compressing position. Where the heels, however, are of unusual 95 height, the feeding movement of the feeding means or slide is liable to carry such extra high heel toward compressing position before the pressure exerting members have separated sufficiently to receive such heel, 100 the result being that the heel to be compressed is either injured or thrown out of the machine altogether. In any event, it strikes one of the pressure exerting members, the upper or die member 6, in the present instance, and fails to reach compressing 105 position. The present invention, therefore, contemplates the provision of means for retarding the feeding movement of the feeding means or causing a pause in its feeding 110 movement to permit the pressure exerting members to sufficiently separate to accommodate the extra high heel between them.

In the illustrated machine and as fully described in the Allen patent, the top lift 115 plate 9 is raised during the first portion of the descent of the reciprocating head, or in other words, there is a differential movement between the side and breast members of the mold and top lift plate as the pressure exerting members separate. This relative movement, as stated in the patent, is sufficient to bring the upper surface of the top lift plate level with the upper surface 120 of the side members of the mold, and this raises the compressed heel which is supported on the top lift plate into the path of the enlargement or shoulder 15 of the feeding and ejecting mechanism heretofore described, by means of which the compressed 125 heel is 130

heel is ejected from the machine, and the feeding mechanism is able to present a heel to be compressed into compressing position between the pressure exerting members.

5 The retardation or pause in the feeding movement of the feeding means or slide may be variously effected, but in the present instance of the invention, a dog 32 is pivotally connected with the reciprocating head 2 by means of a pin 33 passing through the dog 32 and suitable ears or supports 34 projecting from a back plate 35 adapted to be secured to the reciprocating head 2. The dog 32 is normally held in an inclined position as indicated in Figs. 2 and 3, by means of a spring 36, one end of which is connected to the dog at 37, and the other end to the backing plate 35 at 38, the construction being such that the tendency of the spring 36 is to normally hold the dog 32 with its stop face 39 bearing against the backing plate, as indicated in Fig. 2, but permitting the dog 32 to yield downwardly in response to any force tending to move it clockwise, in Fig. 2.

10 25 Pivots mounted on the main frame of the machine is a rocking member which constitutes a part of the retarding device, in the present instance of the invention. The rocking member comprises an arm 40 pivotally mounted at 41 to the lugs 42 projecting from a bracket 43 secured to the main frame 1. The rocking arm 40 carries a roll 44 adapted to be engaged by the rounded end portion 45 of the dog, as the latter 30 35 moves downwardly during the separation of the pressure exerting members. The other arm of the rocker 40 is pivotally connected at 46 with a link 47 which is itself jointed to a collar 48 fixed to the rod 27, the construction being such that upon rocking movement of the rocker 40 clockwise, viewing Fig. 1, the rod 27 will be forced downwardly against the tension of its spring 30, and as such action is incident to the downward movement of the mold which normally imparts feeding movement to the feeding means, it follows that the feeding means will be retarded or caused to pause in its feeding movement when the rocker 40 is 40 45 50 rocked as above described.

The dog 32 may be connected to the mold carrying or reciprocating head 2 in any position desired to cause the actuation of the rocker 40 at a predetermined time relative to the feed movement of the feeding means, so as to cause the retardation or pause in the feeding means at any part of the feeding movement thereof. In the illustrated instance of the invention, however, the retardation or pause in the feeding movement is effected between the commencement and ending of the feeding movement of the feeding means, so that the dog 32 after acting upon the rocker 40 in the manner hereinbefore described, to effect the desired retarda-

tion or pause in the feeding means, passes downwardly past the roll 44 on the rocker, whereupon the roll 44 under the actuation of the spring 30 (Fig. 1) tilts the dog as indicated in Fig. 4, and rides over the dog without influencing the action of the feeding means as the reciprocating head 2 moves upwardly.

It may be desirable at times to alter the time of the retardation or pause in the feeding movement of the feeding means, and one good form of mechanism to this end consists of a threaded adjusting member 49 connecting the link 47 with the rocker 40 as indicated in Fig. 1. This means affords the desired adjustment, but obviously the desired alteration in the pause of the feed movement might be effected by other adjustments.

The operation of the machine will be clear from the construction and function of parts as hereinbefore described, and if it be assumed that a heel has just been compressed and the pressure exerting members are moving in a direction of relative separation, the top lift plate and mold members with which it is associated, will be relatively moved, finally reaching the position as indicated in Fig. 1, where the mold has about reached its lowest position. At this time the surface of the top lift plate 9 will be approximately in the plane of the upper portions of the side and breast mold members to present the compressed heel for ejection from the machine by the shoulders or abutments 15 and 100 the introduction of an uncompressed blank to compressing position.

As the pressure exerting members move in a direction of separation to the position hereinbefore stated, the feeding means will be actuated by the described movement of the reciprocating head 2. As the dog 32 which is secured to the head 2, moves over the roll 44 on the rocker 40 (Fig. 2) it will effect movement of the rocker clockwise from the position indicated in Fig. 2 to that indicated in Fig. 3, thereby causing a retardation or momentary pause in the feeding movement of the feeding means. As the head 2 continues to descend, the roll 44 in Fig. 3 will pass above the surface 45 of the dog and, under the influence of the spring 30 (Fig. 1) will cause the dog to swing into the position indicated in Fig. 4, thereby permitting the rocker 40 to assume substantially its normal position and cause the feeding movement of the feeding means to effect full movement of the heel to compressing position between pressure exerting members. As the head 2 rises from the position in Fig. 4, which is substantially indicative of its lowest position, the roll 44 will ride idly over the dog 32 without substantially affecting the retreating or backward movement of the feeding means.

By adjustment of the dog in its relative location with respect to the rocker, or by adjustment of the connection between the rocker and rod 27, the retardation or pause in the feeding movement of the feeding means may be variously changed to different portions of the cycle of the feeding movement.

What is claimed is:

- 10 1. In a compressing machine, the combination of opposed compression members movable relatively toward and from each other to compress and release a blank, blank feeding means, and additional means acting through the blank feeding means during the relative separating movement of the compression members to delay the insertion of a blank between said members.
- 15 2. In a heel compressing machine, the combination of compression members movable relatively toward and from each other to compress and release a heel, heel feeding means, means for imparting a normal feed movement to the heel feeding means, and means acting during the separating movement of the compression members for modifying the normal feed movement of the feeding means to permit high heels to be placed between the compression members.
- 20 3. In a machine of the class described, the combination of compression members movable relatively toward and from each other to compress and release a blank, a blank feeding slide, means for operating the slide, and means effective during an intermediate portion of the separating movement of the compression members for causing a retardation in the normal feed movement of the slide.
- 25 4. In a machine of the class described, the combination of a relatively movable die and mold to compress and release a blank, a blank feeding slide, means for yieldingly moving the slide to feed a blank, and means acting through the yielding means for modifying the feed movement of the slide during the separation of the die and mold.
- 30 5. In a compressing machine, the combination of a die, a reciprocating mold, means for feeding a blank between the die

and mold, and means actuated during the retreat of the mold from the die for retarding the feeding movement of the feeding means.

6. In a compressing machine, the combination of a die, a reciprocating mold, means for feeding a blank between the die and mold, and means operated by movement of the mold as it retreats from the die for changing the feeding movement of the feeding means.

7. In a machine of the class described, the combination of pressure exerting members movable toward and from each other to compress and release a blank, blank feeding means, and means actuated by movement of one of the pressure exerting members for retarding the feeding movement of the feeding means during the separating movement of the pressure exerting members to permit high as well as relatively low blanks to be fed between the pressure exerting members.

8. In a heel compressing machine, the combination of heel feeding and ejecting means, and means for operating the feeding and ejecting means, including a retarding device acting during a part of the feeding and ejecting movement to retard the normal feeding movement.

9. In a heel compressing machine, the combination of heel feeding and ejecting means, means for operating the feeding and ejecting means, and a retarding device operative during movement of the feeding and ejecting means in one direction to retard the feeding movement of said means.

10. In a heel compressing machine, the combination of a feed slide, compression members relatively movable toward and from each other, means for moving the feed slide to place a heel between the compression members during their movement of separation, and a retarding device arranged to operate during the movement of the feed slide in one direction and be inoperative during its movement in the other direction.

In testimony whereof I have signed my name to this specification.

THOMAS LUND.
